INTERMITTENT INDUCTIVE TRAIN CONTROL SYSTEM

Filed July 15, 1929

INVENTOR,
W. H. Reichard,
BY *Neil A. Weston,*
his ATTORNEY

UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

INTERMITTENT INDUCTIVE TRAIN-CONTROL SYSTEM

Application filed July 15, 1929. Serial No. 378,322.

This invention relates in general to intermittent inductive train control systems, and has more particular reference to an improved trackway inductor immune from false clears due to a short or the like, useable in such systems.

In systems of the character in question, such for example as shown in application 358,577 filed April 27, 1929, by W. H. Reichard, a wayside inductor, controlled in accordance with traffic conditions ahead, is transiently coupled with a car-carried receiver so as to influence such receiver and secondary circuits connected therewith to exert desired controls on the train.

Obviously, it is desirable to make the inductor as far immune as possible to setting up proceed conditions due to false condition of the inductor.

With the above and other objects in view, it is proposed, in accordance with this invention, to provide an inductor having two main windings, so arranged and connected up as to make it practically impossible for it to have effect on the receiver unless clear conditions exist on the trackway.

Further objects, purposes and characteristic features will appear as the description progresses, reference being made to the accompanying drawing showing, in a wholly diagrammatic manner, one embodiment of applicant's invention.

In the drawing:—

The single figure of drawing is a diagrammatic view of one form of applicant's invention as employed in a train control system.

Referring now to the drawing, there is shown a stretch of railway track constituted by track rails 1, divided into usual signal blocks by insulating joints 2, with a wayside signal 3 at the entrance end of each block, controlled in any usual or desired manner (not shown on the drawing), and operating, in any usual manner, a contact finger 5, to different positions, depending on traffic conditions.

Carried on a car, represented diagrammatically by wheels and axles 7, is a receiver constituted by a laminated core C_o in the general form of an H. The receiver and associated

circuits are substantially the same as shown in the above referred to Reichard application.

Carried on the core C_o are two primary windings P, and two secondary windings S, the two primary windings P being connected in series with each other and with a tuning condenser 8, across a source of alternating current, such as an alternator 9. The two secondary windings S are, likewise, connected in series with each other and with a tuning condenser 10, and across a brake applying device EPV, which can be of any usual or desired form and which is normally energized and operates, when de-energized, to exert any desired control such, for example, as giving an automatic brake application.

Located at the entrance end of each signal block, at the signal location, is an inductor, shown in the particular example to be positioned between the track rails 1, and comprising a laminated magnetic core C_r , carrying two spaced control windings W and W^1 , with a condenser 11 bridged across winding W, and a condenser 12 bridged across winding W^1 . The two windings W and W^1 are connected in series with each other and with a capacitor in the form of a condenser 13, and a contact finger 5 controlled in any usual or desired manner, as by the signal 3.

The inductor thus comprises the two main windings W and W^1 , each of which windings, is shunted across the other winding and the condenser 13, when contact finger 5 is in the position corresponding to the clear, or 90° , position of signal 3.

The control of the inductor on the receiver when the receiver passes over the inductor, is similar to that explained in detail in the above referred to Reichard application. Briefly, under clear or safe conditions, at which time contact 5, is in its 90° , or circuit closing position, each of the windings W and W^1 on the inductor exerts a clearing effect on the receiver, so as to not reduce the current normally energizing the device EPV to an extent sufficient to cause it to release and apply the brakes. Under caution and danger conditions, however, contact 5 is in circuit opening position, to thereby open the circuit above referred to as including the

100

two windings W and W^1 . Under these conditions neither of the windings W and W^1 is effective to prevent the core from having a stopping influence on the receiver, so that the current in the EPV is so reduced as to cause it to release and cause an automatic brake application.

The manner in which these clearing and stopping influences of the inductor on the receiver is produced, is similar to that in the Reichard application above referred to. The windings W and W^1 , and the capacitor 13, are so chosen that each winding, when it has bridged across it the other winding and the capacitor 13 in series, is in a circuit having the proper characteristics to exert such a choking effect on the core C_r that the core does not materially disturb the normal inductive relationship of the primary and secondary windings on the receiver. In this manner, the receiver is practically unaffected by the inductor.

If, however, either of the windings W or W^1 has bridged across it only the other winding, or only the capacitor 13, the resulting circuit has such characteristics as to produce a stopping effect on the receiver. This is most likely due to the said circuit permitting a material amount of flux to pass through the core Cr and to thus disturb the normal relationship between the primary and secondary windings on the receiver so that bucking fluxes through the secondaries produce little or no secondary voltages.

35. The condensers 11 and 12, which are bridged across the windings W and W¹, respectively, are optional, but are preferably employed since they serve to increase the ratio of EPV current under clear conditions to the EPV current under caution and danger conditions.

These two condensers 11 and 12, can, if desired, be replaced by a single condenser, positioned outside of the inductor casing, and connected in multiple with condenser 13 but shunted around finger 5, instead of in series with 5, as is condenser 13.

From the above discussion, it should be clear that each winding on the inductor is changed from having a stopping effect when simply bridged by 11 or 12, to having a clearing effect, by bridging across it an inductance constituted by the other winding, and a capacitance constituted by the condenser 13, and that neither winding W nor W^1 is changed from having a stopping effect, to having a clearing effect if there be bridged across it either the inductance only, or the capacitance only.

60 Indicated on the drawing by dotted lines $a-a^1$, $b-b^1$, and c , are various short-circuit conditions which might conceivably arise in practice.

With a cross condition such as produced by wire a , the winding W acts to give a clear-

ing effect on the receiver, since both its normal inductance W^1 and capacitance 13 are shunted out. Under these same conditions however, winding W^1 has bridged across it the condenser 13 but not the winding W and hence this winding W^1 has a stopping influence on the receiver, thereby causing the net influence of the inductor as a whole to be a stopping influence. 70

With a cross such as is produced by wire a^1 , winding W produces a stopping effect, while W^1 might produce a clearing effect. 75

With a cross such as produced by wire b , here again winding W might produce a clearing effect on the receiver, but this could do no harm since the other winding W^1 , having its normal inductance W shunted out, produces a stopping effect.

With a cross such as produced by wire b^1 , W gives a stopping effect, while W^1 might possibly give a clearing effect.

With a cross such as produced by wire c , which shunts out the condenser 13, each of the windings W and W^1 have shunted across it only an inductance in the form of the other windings, and hence each winding W and W^1 produces a stopping effect.

From the above it is seen that a single short circuit in connection with the inductor can produce only a stopping inductor, and cannot set up a false clear influence on the receiver, such as to permit passage over the inductor without incurring an automatic brake application. 95

In order to minimize, to the greatest extent, the possibility of short circuits and crossed wires, it is desirable to include windings W and W^1 , the core Cr and the condensers 11 and 12, in a casing, as indicated by the dotted line 14, and to have condenser 13 positioned externally of this case. 100 103

The above rather specific description of one form of system embodying the present invention, has been given solely by way of illustration, and is not intended, in any manner whatsoever, in a limiting sense. Obviously, this invention can assume many different physical forms, and is susceptible of numerous modifications, and all such forms and modifications are desired to be included by this invention, as come within the scope of the appended claims. 110 115

Having described my invention, I now claim:

1. In an inductor for inductor train control systems, in combination, a core of magnetic material, two distinct spaced control windings on the core, a condenser, traffic controlled means for at times bridging across each control winding, the other control winding and the condenser in series, and a car-carried receiver, positioned to pass over, and be inductively influenced by, the inductor, for stopping or not stopping the car according as the inductor exerts thereon a stopping or a 120
125
130

clearing effect, each control winding being adjusted to exert a clearing effect only if in series with the other control winding and the condenser.

2. In an inductor for inductive train control systems, in combination, a core of magnetic material, two separate spaced control windings on the core, a condenser, traffic controlled means for at times bridging, across each control winding, the other control winding and the condenser in series, and a car-carried receiver, positioned to pass over, and be inductively influenced by each of the control windings by itself for stopping or not stopping the car according as each inductor is not, or is, in series with the condenser and the other control winding.

3. In an inductor for inductive train control systems, in combination, a core of magnetic material, two separate spaced control windings on the core, a condenser, traffic controlled means for at times bridging, across each control winding, the other control winding and the condenser in series and a car-carried receiver, positioned to pass over, and be inductively influenced by, the inductor, for stopping or not stopping the car according as the inductor exerts thereon a stopping or a clearing effect, each control winding being so adjusted as to separately exert a stopping, or a clearing, effect on the receiver, only according as it does not, or does, have bridged across it, said other control winding and the condenser in series.

4. In an inductor for inductive train control systems, in combination, a core of magnetic material, two spaced control windings on the core, a condenser, traffic controlled means for at times bridging, across each control winding, the other control winding and the condenser in series, and a car-carried receiver, positioned to pass over, and be inductively influenced by, the inductor for stopping or not stopping the car according as the inductor exerts thereon, a stopping or clearing effect, each control winding exerting a stopping, or a clearing, effect on the receiver, said control windings and said condenser being so adjusted that the bridging across a control winding of the other control winding only, or the condenser only, produces a stopping effect on the receiver.

5. In an inductor for inductive train control systems, in combination, a core of magnetic material, two spaced control windings on the core, a condenser, traffic controlled means for at times bridging across each control winding, the other control winding and the condenser in series, and a car-carried receiver, positioned to pass over, and be inductively influenced by, the inductor, for stopping or not stopping the car according as the inductor exerts thereon a stopping or a clearing effect, each control winding exerting a stopping, or a clearing, effect on the receiver,

according as it does not, or does, have bridged across it, said other control winding and the condenser in series, said control windings and said condenser being so adjusted that the bridging across a control winding of the other control winding only, or the condenser only, produces a stopping effect on the receiver.

6. In combination with an inductor, a car-carried receiver positioned to inductively pass over the inductor and be influenced by the inductor to exert on the car either a clearing, or a stopping effect, the inductor including a core of magnetic material, and two spaced control windings on the core, each winding exerting a separate stopping or clearing effect on the receiver.

7. In combination with an inductor, a car-carried receiver positioned to inductively pass over the inductor and be influenced by the inductor to exert on the car either a clearing, or a stopping effect, the inductor including a core of magnetic material, and two spaced control windings on the core each exerting a stopping or clearing effect on the receiver, each winding being connectable in circuit with the other winding through traffic controlled means and circuit adjusting means, whereby, when not so connected, to each give a stopping effect on the receiver.

8. In combination with an inductor, a car-carried receiver positioned to inductively pass over the inductor and be influenced by the inductor to exert on the car either a clearing, or a stopping effect, the inductor including a core of magnetic material, and two spaced control windings on the core each exerting a stopping or clearing effect on the receiver, a traffic controlled circuit including the control windings so as to cause each winding to exert a clearing effect or a stopping effect according as the circuit is closed or open.

9. In combination with an inductor, a car-carried receiver positioned to inductively pass over the inductor and be influenced by the inductor to exert on the car either a clearing, or a stopping effect, the inductor including a core of magnetic material, and two spaced control windings on the core each exerting a stopping or a clearing effect on the receiver, said control windings being so arranged as to make it impossible for a single cross connection to make both said control windings exert a clearing effect.

10. In combination with an inductor, a car-carried receiver positioned to inductively pass over the inductor and be influenced by the inductor to exert on the car either a clearing, or a stopping effect, the inductor including a core of magnetic material, and two spaced control windings on the core each exerting a stopping or a clearing effect on the receiver, a traffic controlled circuit including the control windings so as to cause each wind-

ing to exert a clearing effect or a stopping effect according as the circuit is closed or open, said control windings being so arranged as to make it impossible for a single cross connection to make both said control windings exert a clearing effect.

In testimony whereof I affix my signature.
WADE H. REICHARD.
